UNITED STATES PATENT OFFICE.

ISRAEL MINKIN AND LOUIS MAGIDSON, OF DORCHESTER, MASSACHUSETTS.

METHOD OF PROTECTING COMMERCIAL PAPER.

Original application filed September 5, 1924, Serial No. 736,123. Divided and this application filed March 9, 1925. Serial No. 14,088.

To all whom it may concern:

Be it known that we, ISRAEL MINKIN and LOUIS MAGIDSON, citizens of the United States, and residents of Dorchester, in the 5 county of Suffolk and State of Massachusetts, have invented an Improvement in Methods of Protecting Commercial Paper, of which the following description, in connection with the accompanying drawings, 10 is a specification, like reference characters on the drawings representing like parts.

Our present invention is a novel and improved method or process of protecting checks, drafts, acceptances, or other 15 commercial paper, and is a divisional of our prior and copending application Serial No. 736,123, filed September 5th, 1924.

An important feature of our present invention consists in so protecting a check or 20 other commercial paper, that it will be impossible to alter the same subsequently, because of the fact that the characters are not merely impressed or indented in the paper to be protected, but said paper, having been 25 entirely penetrated, or cut through, cannot be restored to its original condition. Our invention is a method whereby a check, for example, will be cut or perforated, and inked or colored, simultaneously.

30 In order to carry out our invention of protecting checks, or the like, by cutting, or cutting and coloring, simultaneously, we provide a platen, forming an oblique knurling, as shown in the drawing, although it 35 will be understood and appreciated that this knurling may assume any form, so long as it carries out our invention. The characters comprising the stamp or die to be perforated through the check to be protected, 40 are also knurled to cooperate with the knurling in the platen. We also provide a coloring means, preferably a ribbon, as herein shown, interposed between the platen and the stamp or die. When it is desired to 45 operate upon or to protect a check, for instance, by certification, as herein shown, the check is positioned between the platen and the stamp or die, whereupon the platen and stamp are brought into contact by any 50 suitable means, and thereupon, the knurling on the platen and stamp will cooperate, completely cutting through the paper the words and figures, and simultaneously forcing 55 through the perforations, thus formed, the

coloring matter from the ribbon. So far 55 as we are informed and aware, it has never been possible or feasible to perforate an entire stamp or design comprising a plurality of lines of characters, through a check or other paper, simultaneously. Therefore, 60 we wish to claim this feature broadly.

We also believe that our novel method of thus cutting an entire stamp or design through paper, and coloring the same simultaneously with said cutting is new, and we 65 also wish to claim this feature herein broadly.

Further features of the invention, novel combinations of parts, and advantages, will 70 be herein more fully pointed out and claimed.

Referring to the drawings, illustrating our invention in conventional form,

Fig. 1 is a plan view of a plate, having thereon a complete certification stamp to be 75 perforated through a paper to be protected;

Fig. 2 is a plan view of a knurled platen to cooperate with the plate shown in Fig. 1; and

Fig. 3 is an enlarged fragmentary detail 80 with the platen and stamp in cooperating position, and a ribbon and check interposed therebetween.

It will be appreciated that we have illustrated in the attached drawing but one form 85 of platen and stamp for carrying out our invention, and that the platen and stamp, instead of being flat as herein illustrated, may be of a concavo-convex form, or any other form so long as the platen and stamp 90 are parallel to each other, and can carry out the feature of cutting the entire design through a sheet of paper, simultaneously. For purposes of illustration only, therefore, we have shown the form in the attached 95 drawing wherein is illustrated a plate 1, having thereon a plurality of letters, figures, or other characters 2, these characters being knurled. It will also be appreciated that this plate 1 may have thereon any design, or 100 any characters, for any purpose of protection. In the form shown in Fig. 1 we have illustrated a certification stamp, with the usual certification characters thereon. In the plate 1 is illustrated a longitudinal opening 3, wherein a date 4 may be inserted, such date to be changed at will. 105

Fig. 2 illustrates a platen 5, knurled to

cooperate with the characters, 2 on the plate 1.

In Fig. 3 the platen 5 and characters 2 are shown in cooperating position about to perforate a check 6. A ribbon 7 is positioned between the check and the knurling on the platen 5, although this position of ribbon may be reversed, if desired. Upon operation of any suitable mechanism to bring the platen and stamp into contact, the knurling 8 on the characters 2, will penetrate the check or other paper 6, and enter the valley 9 in the platen 5, thus cutting, penetrating, or lacerating entirely through the check 6. The ribbon 7 will not be torn or injured by reason of this penetrating action, because the ribbon being relatively soft, compared with the paper, will "give" so that it will conform to the knurlings on the characters and platen; whereas the paper being soft will not "give," but will be penetrated by the points or edges of said knurling. It will be appreciated that all of the characters on the stamp or design are thus knurled to cooperate with knurling on the platen 5, so that the entire design will be perforated through the check, simultaneously. If desired, we may utilize our present invention without a ribbon or other coloring means, relying upon the perforating action of the stamp to protect the check, but it will be appreciated that by the use of the ribbon, in conjunction with the cutting members, a protecting design is produced upon a check, or the like, which will be ineffaceable, because the cutting action has so weakened the cut portions, that any attempt to eradicate the same, results in the destruction of the design, and the instant detection of the attempted alteration.

The carrying out of our novel method will be instantly apparent. It being desired to protect, for example, a check, the check is positioned between the knurled platen and knurled stamp, either with or without the ribbon interposed therebetween, the platen and stamp are brought into contact with each other, whereupon an unalterable and ineffaceable design is cut or perforated

through the paper, and preferably simultaneously colored.

In our copending application, Serial No. 736,123, we have illustrated one apparatus for carrying out our novel method, but it will be appreciated that we are not limited thereto, but may use any apparatus or device which embodies the broad feature of simultaneously cutting, or simultaneously cutting and coloring a design comprising a plurality of lines of characters.

Our invention is further described and defined in the form of claims as follows:

1. The improved process of protecting commercial paper, which consists in perforating a design through the paper, in conjunction with a ribbon to simultaneously color the same.

2. The improved process of protecting commercial paper, which consists in perforating therethrough a design comprising a plurality of lines of characters, and simultaneously coloring the same by means of a ribbon.

3. The improved method of protecting commercial paper, which consists in positioning said paper between a platen and a stamp, providing a coloring ribbon between said platen and stamp, and bringing the platen and stamp into contact, whereby an impression is cut completely through the paper, and simultaneously colored.

4. The improved method of protecting commercial paper, which consists in positioning said paper between a platen and stamp, said stamp comprising a plurality of lines of characters, said platen and stamp having cooperating knurlings thereon; providing a coloring ribbon between said platen and stamp, and bringing the platen and stamp into contact, whereby an impression is cut completely through the paper, and the portions surrounding said perforations are simultaneously colored.

In testimony whereof, we have signed our names to this specification.

ISRAEL MINKIN.
LOUIS MAGIDSON.
